UNITED STATES PATENT OFFICE.

JAMES PERCY WINN, OF SUTTON COLDFIELD, ENGLAND.

DEVICE FOR PROTECTING THE HUMAN EARS.

Application filed September 27, 1924, Serial No. 740,378, and in Great Britain December 15, 1923.

This invention comprises a device or appliance for protecting the human ears, and it has for its purpose to relieve the ears from noise occasioned for instance by one suffering with irregular or defective heart action.

In such circumstances when the ear is rested upon a pillow or other supporting device, noise, vibration or beating is set up in the head, and it is the object of the present invention to avoid or reduce this, the invention having the advantage that it conduces to sleep or rest or to increased comfort in sleep or rest.

Accordingly the present invention comprehends a device or appliance in the form of a pad or pads adapted to be placed over the ear or ears, and which pad or pads is or are adapted to be secured to the head by fastening devices which preferably are adjustable. The pad or each pad has a recess, opening or space adapted to be located in relation to the duct which communicates with the drum of the ear. This recess or space may be located transversely of the pad as for instance in a vertical position so that ventilation is permitted, but alternatively the opening may be a circular one in a pad which may be of annular form. The pad is thus adapted to form a cushion between the ear and the part upon which the latter rests.

In order to avoid undue pressure upon the ear I advantageously incorporate a second pad above that which is located in relation to the ear. This second pad serves to distribute the supporting means for the head when the device is in use.

Either or both of the pads may be of an appropriate non-metallic material reinforced with metallic or other relatively rigid material, and in cases in which the air space extends across the ear-pad in a vertical direction the bearing part of the pad behind the ear may project from the reinforcing plate more prominently than that part of the pad which bears upon the fore part of the ear. This desideratum may be obtained by suitably bending the reinforcing member when composed of sheet metal, and the pad-sections at front and rear may be detachable from the reinforcing member. Alternatively the pad may be composed of moulded rubber with fore and rear bearing portions of a hollow character, the transverse part from which these portions project being stiffened if desired, as for instance by incorporating a metal plate.

The additional pad which is located above that in the region of the ear is also advantageously reinforced with sheet metal.

The pads or the bearing portions thereof may be of any appropriate material such as fabric filled with any suitable packing or alternatively they are of a character such that they may be inflated or filled with water or other liquid.

The pads or bearing portions thereof may each be provided with a silk or other covering which is preferably detachable.

Such a device thus functions to leave the orifice of the ear open to the air while rendering it impossible for any object against which the head or ear is placed to close this orifice without an air space or pocket intervening.

In order that this invention may be clearly understood and readily carried into practice, reference may be had to the appended sheet of explanatory drawings on which

Figure 1 is a side elevation illustrating the embodiment of the present invention.

Figure 2 is a front elevation of the embodiment shown in Figure 1.

Figure 3 is a side elevation of the embodiment shown in Figures 1 and 2 as viewed in a direction opposite to that obtaining in the case of Figure 1.

Figure 4 is an elevation similar to Figure 3 but with that part of the device which occurs on the left of the head omitted.

Figure 5 is a sectional plan of the part shown in Figure 4.

Figure 6 illustrates separately certain parts of the device shown in Figures 1 to 4.

Figure 7 is a sectional plan of the central element shown in Figure 6.

Figure 8 illustrates in sectional plan certain parts omitted in Figures 1 to 4.

Figure 9 illustrates in sectional plan a modification of the structure shown in Figure 5.

In a convenient embodiment of the present invention I provide a sheet metal frame *a* or reinforcing member, flanged at the rear side as at *b* and provided with inturned tongues *c* which are adapted detachably to carry the front pad section *d*. This pad section is provided with a strip of elastic *e* which embraces the tongues *c*, the ends of which are bent at right angles as at *f* to retain the pad. At a position between the tongues which occur substantially at top and bottom of the frame or reinforcing member

an intermediate tongue *q* occurs which forms a base for the pad spacing it from the body of the frame. The extremity of this tongue is bent inwardly as at *h* to bear upon the inner surface of the main web of said frame and on the other side of the frame only the tongues *i* at top and bottom utilized to carry the pad section are employed, the pad section being adapted to bed directly upon the inner surface of the plate.

Elongated openings *j* are provided at top and bottom in the mid-portion of the frame for the connection of attachment devices.

The pad *n* which is located above that last described may be of similar material reinforced by a plate of metal *k* which is cranked or off-set at a mid-position to accommodate at the outer side of the pad a ring *l* hereinafter to be described, which is associated with the fastening devices. The cranking or off-setting of the plate *k* enables the outer face of this ring to lie flush with the outer bearing parts of the pad, while inwardly the padding is restricted in its thickness at a central point so that the head is relieved from any effects of the cranked or off-set part of the plate.

An elastic or other connecting device *m* extends from the top of the ear pad to the ring *l* at the back of the head pad *n* and another similar connecting device *o* extends from the upper part of this ring and is adapted to pass over the head to a similar ring located above the other ear. With this other ring another head pad and ear pad may be associated, but otherwise a connecting element *p* extends from the bottom of the ring and is adapted to be passed around the chin and to be secured to a connecting element *q* depending from the bottom of the reinforcing plate of the ear-pad on the other side of the head.

Two other securing devices *r* *s* are provided laterally from the rings and connecting the latter. One of these members may extend around the fore-head and the other around the rear part of the head.

All of the fastening members are preferably of an adjustable character as for instance by the utilization of suitable buckle devices *t*.

The modification shown in Figure 9 illustrates a pad composed of rubber having hollow bearing parts *u*.

The rings provide for self alignment and universal movement of the fastening devices which latter are advantageously throughout of an elastic character, and said fastening devices are advantageously detachable both from the ear pad and from the supplementary pad. The latter may at its outer surface be provided with loops through which the laterally extending members pass in a manner such that the fastening devices are thereby secured detachably to the pad.

While I have mentioned fabric filled with a suitable packing as an appropriate medium for use as the bearing portions of the pads, and have suggested alternatively that the pads may be composed of rubber, in each case with metal or appropriate non-metallic material as a supporting medium the materials with which the pads are composed may be modified considerably and chamois or other soft leather, oiled silk and skins packed with sponge rubber, cotton wool or filling may be mentioned as alternative materials for the pad proper, while the reinforcing elements may for instance be composed of gutta-percha, horn, bone, ivory or appropriate compositions.

Having described my invention what I claim and desire to secure by Letters Patent is:—

1. A device for relieving the human ears of internal noises and beatings and comprising a pad having a frame, spaced ear engaging cushions located along the side edges of the frame and having an opening between such cushions affording open communication between the ear opening and the atmosphere, a pad engageable with the head above the ear, means for holding the pads in position on the ear and head, and including an adjustable head encircling element extendible over the top of the head and under the chin, and an adjustable head encircling element extendible around the forehead and also around the back of the head.

2. A device for relieving the human ears of internal noises and beatings and comprising a pad having a frame, spaced ear engaging cushions located along the side edges of the frame, and means on the frame for securing the cushions thereto, the space between the cushions affording an unobstructed opening affording communication between the ear opening and the atmosphere when the pad is applied to the ear.

3. A device for relieving the human ears of internal noises and beatings and comprising a pad having a frame, spaced ear engaging cushions located along the side edges of the frame and having an opening between such cushions and affording open communication between the ear opening and the atmosphere, a pad engageable with the head above the ear, means for holding the pads in position on the ear and head, and including an adjustable head encircling element extendible over the top of the head and under the chin, and an adjustable head encircling element extendible around the forehead and also around the back of the head, said head encircling elements having rings incorporated therein to permit of proper alignment of the same.

In testimony whereof I hereunto affix my signature.

JAMES PERCY WINN.
